UNITED STATES PATENT OFFICE.

MANUEL BOUZO, OF HABANA, CUBA.

DEVICE FOR ADJUSTABLY CONNECTING THE YOKE TO THE POLES OF CARTS.

1,279,238.

Specification of Letters Patent. Patented Sept. 17, 1918.

Application filed February 19, 1918. Serial No. 218,089.

To all whom it may concern:

Be it known that I, MANUEL BOUZO, a citizen of the Republic of Cuba, and a resident of Habana, Republic of Cuba, have invented a certain new and useful Device for Adjustably Connecting the Yokes to the Poles of Carts, of which the following is a full, clear, and exact specification.

This invention relates to the connection of the yoke to the pole of the ox drawn carts and its object is firstly to provide an adjustable device to such end thus preventing the inconveniences occasioned by the wooden blocks and ropes at present in use, which do not always offer the same resistance in view of the yielding of the rope, and secondly, to provide a device which will be detachable, a fact that is of considerable advantage in such cases when it is necessary to separate the couple of oxen from the cart, such as occurs with the carts used for the hauling of sugar cane when reaching the mill, to dump the cart and discharge the load therefrom on to the carrier to the grinding machine.

In the annexed drawings:

Figure 1 is a front view of a yoke secured to a cart pole by means of the device which is the subject-matter of this invention.

Fig. 2 is a vertical cross-section of the yoke, taken on the line II-II of Fig. 1 and looking in the direction of the arrows.

Fig. 3 is an upper plan view of the device.

Fig. 4 is an enlarged longitudinal vertical section of part of the device.

Fig. 5 is a detail showing in perspective the curved bolts and the loop forming a part of the device.

Fig. 6 is a front elevation of the shooting hook of the device.

Fig. 7 is a rear elevation of said shooting hook.

Fig. 8 is a side elevation of the same shooting hook, in its closed and opened position.

And Fig. 9 is a perspective view of the key-bar used to open the shooting hook.

This device comprises two bolts 1, 2, having their upper ends threaded and their lower ends slightly curved and terminating in eyes 3, 4 to which are connected the ends 50 of a metallic loop 5, the upper threaded ends of said bolts passing freely or without screwing through holes in an end portion of a horizontal plate 6 of rectangular shape and

said bolt ends carrying on said plate 6, nuts 7 and 8. The opposite end portion of said plate 6 is provided with holes through which pass freely or without screwing, the upper threaded ends of a U-shaped piece 9, whose lower branch is curved as shown at 9' and 9'', said upper piece ends bearing on said plate 6 by means of nuts 10 and 11. From the lower portion of said U-shaped piece is pending, through an eye 12 formed in its upper part, a support 13, curved at its lower half, and on whose lower end is pivoted at 14 a shooting hook 15 which is held in raised position or fixed to its support 13 by means of a clamp 16 pivoted on 17 on the support 13 and provided with a stem 18, this clamp embracing said hook when in its raised position. On this hook 15 laces a ring 19 mounted on said loop 5.

Plate 6 shows three holes longitudinally aligned the central one of which is of plain surface and the two others of threaded surface. Through the plain hole passes a vertical guiding bolt 20 which presents on its upper end a head 21 and is fixed at its lower end by screwing or by any other means to a rectangular plate 22 below and parallel to plate 6 and narrower than the latter, said plate 22 being located between the two bolts 1 and 2 and between the two lateral branches of the U-shaped piece 9. Through the threaded holes of plate 6 there are passed 85 screws 23 and 24, presenting on their upper ends eyes 25 and 26 and terminating at their lower ends in the form of bolts of less diameter which pass through holes in the lower plate 22 and have their lower ends countersunk in corresponding recesses of plate 22, whereby the screws 23 and 24 are held fast by plate 22 but are rotatory upon themselves. In a similar manner, on the plain lower thinner ends of screws 23 and 24 are mounted 90 above plate 22 washers 27 and 28 that prevent the downward movement of these screws 23 and 24 and on these screws and above plate 6 there are mounted counter nuts 29 and 30.

This device is mounted on the yoke 31 and the pole 32 of a cart so that the latter and the block 33 be embraced by the two bolts 1 and 2, the U-shaped piece 9, the support 13, the shooting hook 15, and the metallic loop 105 5; the yoke 31 passing between both bolts

1 and 2 and between the two vertical branches of U-shaped piece 9, the lower plate 22 bearing on upper face of yoke 31. To adjust the device, the bolts 1 and 2 and the 5 U-shaped piece 9 are tightened upon yoke 31, block 33 and pole 32 by properly turning the screws 23 and 24 by means of a bar 34 applied to the upper eyes 25 and 26 of said screws so that the upper plate 6 may 10 run up as a sliding nut exerting pressure on nuts 7 and 8 and the counter nuts 29 and 30 are then tightened on screws 23 and 24 against plate 6. To detach the device or to 15 separate the yoke 31 from the pole 32 it is only necessary to shoot off the hook 13 that locks the device on the yoke and pole, to which end is used the same bar 34 which carries on its end a block 35, provided with a hole 36 and which properly forms a key by 20 mounting the hole 36 over the stem 18 of clamp 16, as shown in Fig. 2 of the drawing and said clamp is turned upwardly on its pivot 17 so as to disengage the shooting hook 15, as indicated in dotted lines on Fig. 8 of 25 the drawings, whereby and owing to the tension of loop 5 said hook 15 turns downwardly on its pivot 14 thus letting loose the ring 19 of said loop and the device free from the pole 32 and yoke 31.

30 In order to lock the device again, the yoke 31 is placed once more on pole 32 with the block 33 intermediate so that the latter and the pole 32 be embraced by bolts 1 and 2 on one side the U-shaped piece 9 and support 35 13 and hook 15 at the other side, and the loop 5 is raised, lacing the ring 19 on hook 15 which in turn is raised on its pivot 14, and over its upper end the clamp 16 is lowered on its pivot 17 until holding in its locked 40 position.

It is obvious that the form of the different pieces forming the device can be slightly changed without altering the essential character of the invention, which is as pointed 45 out in the following claims.

What I claim is:

1. A device for adjustably connecting a yoke to the pole of a cart, comprising substantially U-shaped locking means embracing 50 the pole and through which means passes the yoke, a plate slidably mounted on the upper portions of said locking means, nuts on the threaded ends of said locking means, another lower plate parallel to the first one 55 and which bears on the yoke, and screws rotatably confined at their lower ends in the lower plate and threaded through the upper plate.

2. A device adjustably connecting the 60 yoke to the pole of carts comprising substantially U-shaped locking means embracing the pole and through which means passes the yoke, nuts on the threaded ends of said locking means, a plate slidably mounted on

the ends of the locking means underneath 65 the nuts thereof, another lower plate parallel to the first one and which bears on the yoke, screws rotatably confined at their lower ends in the lower plate and screwed through threaded holes in the upper sliding plate, 70 and a guiding bolt fixed at its lower end to the lower plate and passing through the upper sliding plate.

3. An improved device for adjustably connecting the yoke to the pole of carts, comprising two bolts at one side and a U-shaped piece at the other side, there being connected to the lower ends of the bolts a loop that is laced to a shooting hook pending from the lower end of the U-shaped piece, the pole 80 being located between the bolts at one side and the U-shaped piece at the other side and the yoke passing between both bolts and between the two lateral branches of the U-piece, adjustable means above the yoke for 85 tightening the bolts and the U-piece against the yoke and pole, and means for locking the shooting hook.

4. An improved device for adjustably connecting the yoke to the pole of carts comprising two bolts at one side which are provided with nuts on their upper threaded ends and a U-shaped piece at the other side which is provided with nuts on the upper threaded ends of its lateral branches, there 90 being connected to the lower ends of the bolts a loop that is laced to a hook rotatably mounted on a support pending from the lower end of the U-shaped piece, the pole 95 being located between the bolts at one side and the U-shaped piece at the other side and the yoke passing between the two bolts and between the two lateral branches of the U-shaped piece, adjustable means above the 100 yoke for tightening the bolts and the U-piece 105 against the yoke and pole, and a clamp rotatably mounted on the support of the hook to lock the latter.

5. An improved device for adjustably connecting the yoke to the pole of carts comprising two curved bolts at one side which are provided with nuts on their upper threaded ends and a U-shaped piece at their other side which is provided with nuts on the upper threaded ends of its lateral 115 branches, a metallic loop connected at its ends to the lower I-shaped ends of the bolts and carrying a ring on its central portion, a hook rotatably mounted on a support pending from the lower end of the U-shaped 120 piece and through which the ring of the loop is inserted, a clamp pivotally mounted on the hook support and provided with a stem, this clamp in its downward position serving to lock the hook on its support, the pole 125 being located between the bolts at one side and the U-shaped piece at the other side, the yoke passing between the two bolts and the

two lateral branches of the U-shaped piece, a plate slidably mounted on the upper ends of the bolts and of the U-shaped piece and underneath the nuts thereof, another lower 5 plate parallel to the first one and which bears against the yoke, screws with eyes at their upper ends and rotatably confined at their lower ends in the lower plate and which are screwed through threaded holes in the sliding upper plate, and a guiding 10 bolt fixed at its lower end to the lower plate and passing through the sliding upper plate.

In witness whereof I affix my signature.

MANUEL BOUZO.
